UNITED STATES PATENT OFFICE.

FANNIE M. HELM, OF ST. MARYS, KANSAS.

DESIGN FOR A HANDKERCHIEF-SUPPORTING DEVICE.

49,184.

Specification for Design.

Patented June 13, 1916.

Application filed November 6, 1915. Serial No. 60,152. Term of patent 14 years.

To all whom it may concern:

Be it known that I, FANNIE M. HELM, a citizen of the United States, residing at St. Marys, in the county of Pottawatomie and State of Kansas, have invented a certain new, original, and ornamental Design for a Handkerchief-Supporting Device, of which the following is a specification, reference being had therein to the accompanying drawing, forming part thereof, wherein—

Figure 1 is a perspective view of a hand-

kerchief supporting device, showing my new design. Fig. 2 is a top plan view of a handkerchief supporting device, showing my new design.

I claim:

The ornamental design for a handkerchief supporting device, as shown.

In testimony whereof I hereunto affix my signature.

FANNIE M. HELM.
